CLAIM

The ornamental design for a two-piece toilet, as shown and described.

DESCRIPTION

FIG. 1 is a perspective view of a two-piece toilet;
FIG. 2 is a top view of the two-piece toilet of FIG. 1;
FIG. 3 is a front view of the two-piece toilet of FIG. 1;
FIG. 4 is a bottom plan view of the two-piece toilet of FIG. 1;
FIG. 5 is a rear view of the two-piece toilet of FIG. 1;
FIG. 6 is a right side view of the two-piece toilet of FIG. 1;
and,

FIG. 7 is a left side view of the two-piece toilet of FIG. 1.

The broken lines showing of portions of the toilet are included for the purpose of illustrating the toilet and form no part of the claimed design.
